CLAIM

The ornamental design for a configurable product mount, substantially as shown and described.

DESCRIPTION

FIG. 1 is a perspective view of a configurable product mount;

FIG. 2 is a top view thereof;

FIG. 3 is a back view thereof;

FIG. 4 is a front view thereof;

FIG. 5 is a left view thereof;

FIG. 6 is a right view thereof;

FIG. 7 is a bottom view thereof;

FIG. 8 is another perspective view thereof;

FIG. 9 is a perspective view of the configurable product mount in combination; and,

FIG. 10 is another perspective view of the configurable mount in another combination.

The broken lines in the Figure drawings are included for the purpose of illustrating environment and form no part of the claimed design.
